UNITED STATES PATENT OFFICE.

WILLIAM ROBBINS AND HARRY F. BRYAN, OF CHICAGO, ILLINOIS.

ENGINE-GOVERNOR.

1,334,555.

Specification of Letters Patent. Patented Mar. 23, 1920.

Application filed March 19, 1917. Serial No. 155,641.

To all whom it may concern:

Be it known that we, WILLIAM ROBBINS and HARRY F. BRYAN, citizens of the United States, residing at Chicago, in the county of Cook and State of Illinois, have invented a certain new and useful Improvement in Engine-Governors, of which the following is a specification.

This invention relates to engine governors and is designed more specially to act as a speed limit governor for engines for motor vehicles. Motor vehicle engines are different from ordinary constant speed engines in that they are called upon at various times to operate at widely different speeds. They are also subject to great and sudden variations in load due to the varying conditions of the surface of the roadway and the grade thereof. On account of the variations in road conditions and grades, there is no constant relationship between the speed of the engine and the amount of motive fluid supplied thereto. For example, in the case of an engine controlled by a plain throttle, the throttle valve may be wide open and yet if the vehicle is heavily loaded and going up hill the engine speed may be very low. Conversely, in going down hill with a smooth road, the engine may run at high speed even with the throttle partly or entirely closed. The general object of our invention is to provide means for automatically limiting the speed at which a motor vehicle engine may be run, and at the same time, afford the driver full control over the engine so long as the engine is running below the maximum permissible speed. We do not herein claim this idea broadly as it is disclosed in a co-pending application filed by us March 12th, 1917, Serial Number 154,138. The present invention resides more particularly in certain refinements and structural improvements, among which may be mentioned, first, the idea of making a direct mechanical connection between the controlling mechanism of the engine and the armature of the electro-magnetic device which operates in harmony with the speed of the engine; second, the idea of producing a rotary armature; third, the idea of neutralizing the effects of gravity, and fourth, the provision of advantageous expedients of construction and arrangement which will be hereinafter more fully described.

In order to explain the invention in a simple and advantageous form, we have chosen to illustrate it in connection with an explosion engine, the speed whereof is controlled by a plain throttle valve located in the intake which leads to the manifold. In the drawings,

Figure 1 is a side elevation of the assembled mechanism shown in connection with the engine.

Fig. 2 is a sectional view of the throttle valve and governing mechanism taken on the line 2--2, Fig. 1.

Fig. 3 is an elevation of the parts shown in Fig. 2. The view is taken looking toward the left with the cover removed.

Fig. 4 is a sectional view on the line 4--4, Fig. 2.

Fig. 5 is a plan view chiefly in section on the line 5--5, Fig. 1, and

Fig. 6 is a diagrammatic view of the governing system as a whole.

Similar numerals refer to similar parts throughout the several views.

Referring first to the diagram, Fig. 6, the engine A has a generator B driven from the engine shaft and connected by two conductors C, C to the controlling device which is indicated in general by D. The controlling valve hereinafter mentioned controls the flow in the intake E leading to the engine. Air is supplied through the pipe F and fuel through the pipe G. A rod H affords means for manual control.

Referring now more particularly to Figs. 1 to 5 inclusive, the intake E is provided with a throttle valve 1, rigidly fastened to a shaft 2, which is journaled in ball bearings 3, 3, supported in a housing consisting in the present case of a main casting 5 provided with two covers 6 and 7. Rigidly fastened on shaft 2 is an armature having two pole pieces 9, 9 adapted to be attracted to the pole pieces 10, 10 of an electromagnet, energized by windings 11, 11. These windings are energized through the conductors C, C, and are arranged in line with each other with the armature between them. The pole pieces of the armature are in the form of two similar segments arranged diametrically opposite to each other. The result is, they are balanced and not affected by gravity. A spiral spring 14 is fastened at one end to shaft 2 and at the other end to a slotted link 15 through which

passes a stud 16 by which the link may be adjustably secured to the housing to regulate the tension of the spring.

When the engine is running, an increase in speed will increase the output of the generator and draw the pole pieces 9, 9 over toward the pole pieces 10, 10 against the force of the spring. This tends to move the valve 1 toward closed position. The amount 10 of movement will depend upon the speed of the engine, and the parts are so designed that under ordinary running conditions when the engine reaches the speed for which the governor is set, the valve will be held 15 in the position which will produce that speed. As the speed increases, the valve moves more closely shut, and as it decreases from said predetermined speed, the valve moves farther open. Thus, the valve 20 "floats", as it were, back and forth and tends to maintain the speed at approximately the value for which the device is set.

The manual control is operated through a rod H, previously mentioned, the lower 25 end of this rod being connected to the free end of an arm 18 which is fastened to a rock shaft 19, journaled in the casing. This rock shaft passes into the casing and is there connected to a rocker arm 20 which 30 co-operates with an arm 21 rigidly fastened to shaft 2. The rocker arm has a head 22 which engages a shoulder 23 on arm 21. The parts are so designed that when arm 20 is rotated by the operator in a clockwise 35 direction, Fig. 4, it will rotate arm 21 in an anti-clockwise direction to close valve 1, but will have no effect to move arm 21 toward open position.

The operation of the device will be evident. The spring 14 tends to keep the parts 40 in the position shown in Figs. 2, 3 and 4, at which time the valve will be wide open. When the engine is running, it will cause the rotating armature to be rotated toward 45 closed position in opposition to the force of the spring and, as previously explained, will tend to keep the speed of the vehicle within reasonable limits of the speed for which the governor is set. The operator 50 may partially or entirely close the valve at any time by pulling on rod H and thus rotating arm 20 in a clockwise direction (Fig. 4) and causing it to rotate arm 21 and shaft 2 in an anti-clockwise direction, but as the 55 rocker arm 20 is not attached to arm 21, it has no ability to force it in any direction except toward closed position. Thus the operator can force the valve closed but cannot force it open.

60 It will be seen that the device consists of comparatively few parts, which are of simple form and are effectually inclosed within a housing. As the armature has a rotary motion, it is in no danger of binding and, furthermore, as it is balanced on

opposite sides of the shaft, gravity has no effect upon it. As the armature and valve are direct connected on the same shaft, there is no opportunity for lost motion, and in addition to this, the number of parts 70 is reduced to a minimum. It will also be noted that the valve "floats" in the sense that it moves gradually back and forth by infinitesimal increments in proportion to the variations of engine speed. 75

Another advantage in this construction in which the governing apparatus works directly on the throttle valve of the mixing device, is that it dispenses with any auxiliary valve and hence avoids any possibility 80 of "pocketing" fuel vapor or gas between the main and supplemental valves.

Furthermore, as the governing device operates directly upon the throttle valve of the mixing device, the proper operation of 85 the mixing device is assured, and there is nothing to obstruct the passage of the vapor in the manifold.

Having thus described our invention, what we claim as new and desire to secure by 90 Letters Patent, is:—

1. Means for controlling the speed of an internal combustion engine comprising an electric generator mechanically driven by the engine, an electromagnetic winding in 95 circuit with the generator whereby the energization is variable proportionately to the engine speed, a rotatable armature, and a fuel valve for the engine actuated by the armature, the angular position of the armature and hence the position of the valve being variable by infinitesimal increments in practical correspondence with the energization of the winding and hence of the engine speed. 100

2. An engine speed governor having a throttle valve for controlling the supply of motive fluid to the engine, a rotating armature for operating said valve, the amount of movement of the valve following by infinitesimal increments the amount of movement of the armature, an electromagnetic winding, which, when energized, causes the armature to rotate in a direction to close the valve, the amount of movement of the armature depending upon the intensity of energization of the winding, an electric generator connected to and operated by the engine in direct proportion to the speed of the engine, the output of the generator depending 110 upon the speed of the generator and the amount of energization of the winding depending upon the output of the generator, and manually operated means having a one way engagement with said valve whereby it 120 is capable of moving the valve toward closed position and incapable of moving it toward open position. 115

3. A speed limit governor for variable speed engines, having an electric generator 130

driven by the engine, a pair of electro-magnetic windings in line with each other energized by said generator, a rotary armature mounted between said windings and having 5 two balanced pole pieces on opposite sides of their axis, a spring for normally holding said pole pieces out of line with said windings, a valve rigidly connected to said armature for controlling the speed of the engine, 10 and manually operated means operative upon said valve only in the direction to close the same.

4. An engine speed governor for variable speed engines having an electric generator 15 driven by the engine, an electro-magnetic winding energized by said generator in pro-

portion to the speed of the engine, a rotary armature coöperating with said winding, an arm connected to said armature and rotatable therewith, controlling means mechanically connected to said arm for controlling the speed of the engine, and a manually operated rocker arm having a one way engagement with the first mentioned arm whereby it is capable of rotating it in a direction to close the controlling means and is without ability to move it in a direction to move the controlling means toward open position. 20 25

In witness whereof we have hereunto subscribed our names.

WILLIAM ROBBINS.
HARRY F. BRYAN.
